UNITED STATES PATENT OFFICE.

MICHAEL R. QUINN, OF KENT, OHIO.

HANDKERCHIEF.

1,327,062.

Specification of Letters Patent.

Patented Jan. 6, 1920.

Application filed July 10, 1919. Serial No. 309,967.

To all whom it may concern:

Be it known that I, MICHAEL R. QUINN, a citizen of the United States, residing at Kent, in the county of Portage and State of Ohio, have invented certain new and useful Improvements in Handkerchiefs; and I do hereby declare the following to be a full, clear, and exact description of the invention, such as will enable others skilled in the art 10 to which it appertains to make and use the same.

The present invention relates to a handkerchief or sheet of fabric, and aims to fold and form opposite corners of the handkerchief or sheet so that said corners or ends of the article can be conveniently attached after the article is passed or wrapped around the neck, waist, or other part of the body, in order that the handkerchief can be used 20 as a napkin, scarf, apron, bandage and the like.

A further object is the provision of a handkerchief folded on a diagonal line between opposite corners and having such 25 corners formed with a knob or button at one end, and an eyelet or buttonhole at the other end, providing for the convenient connection of said ends in using the handkerchief as a napkin, scarf, apron, bandage or 30 the like.

With the foregoing and other objects in view, which will be apparent as the description proceeds, the invention resides in the construction and arrangement of parts 35 hereinafter described and claimed, it being understood that changes can be made within the scope of what is claimed without departing from the spirit of the invention.

The invention is illustrated in the accompanying drawing, wherein—

Figure 1 is a plan view of the handkerchief embodying the present improvements.

Fig. 2 is an enlarged detail view of one end showing the eyelet or buttonhole.

Fig. 3 is an enlarged detail view of the other end of the article showing the knob or button.

Fig. 4 is a perspective view of the article as used as a napkin, scarf or apron with 50 the ends attached together.

A handkerchief or similar sheet 1 of fabric is used, for the purposes of the present invention, and is folded or doubled on a diagonal line between opposite corners, thereby 55 providing a triangular napkin, scarf, apron, bandage or similar article, the opposite ends

of which are formed to provide interengaging means. Thus, one end portion of the doubled or folded handkerchief is folded and rolled into a ball or knob 2, and a 60 thread, string or other binding element 3 embraces the material behind said knob or button, to provide a neck therefor, and to hold the material in shape.

At the opposite end, the corner portion of 65 the handkerchief is folded back, as at 4, against one side of the body of the sheet, with the tip or corner folded back against the diagonal fold line of the handkerchief or sheet, and one edge of the portion 4 extending diagonally and stitched, as at 5, between the edges of the triangular article, and the other edge 6 of the portion 4 stitched to the article along the diagonal fold line. This provides a reinforced corner portion of 70 four thicknesses of material, which is provided with an eyelet or buttonhole 7. This folding back and sewing of the portion 4 not only reinforces the eyelet or buttonhole portion, but also provides a blunt end for the 75 article whereby the use thereof is rendered more convenient and efficient.

The article can be used as a napkin, scarf, apron, bandage, or the like, and after being passed or wrapped around the body, the 80 knob 2 can be pushed through the eyelet or buttonhole 7, which will attach the ends of the article together, thereby holding it in place, the eyelet or buttonhole being of about the same or slightly smaller diameter 85 than the knob 2. When the handkerchief is used as an apron it will pass only once around the body, whereas when it is used as a napkin or scarf around the neck, it will generally pass twice around the neck before 90 the ends are attached. The handkerchief 95 can also be used as a bandage to be wrapped around the arm or leg and then fastened by inserting the knob through the eyelet. Thus, the handkerchief provided with the 100 features illustrated and described will be of general utility, aside from its ordinary use.

Having thus described the invention, what is claimed as new is:—

1. A handkerchief or similar sheet folded on a diagonal line and formed at its opposite ends with a knob and eyelet.
2. A handkerchief or similar sheet folded on a diagonal line, the end portions being folded and secured, one to form a knob, and 110 the other being provided with an eyelet for the knob.

3. A handkerchief or similar sheet folded on a diagonal line and having its end portions folded, one to form a knob, and the other to form a reinforcement, said reinforcement having an eyelet for the passage of the knob, and a binding element embracing the first named portion behind the knob to form a neck therefor.

In testimony whereof I have signed my name to this specification in the presence of 10 two subscribing witnesses.

MICHAEL R. QUINN.
